UNITED STATES PATENT OFFICE.

GEORGE R. ADAMS, OF HILLSBORO, TEXAS.

LIFTING-JACK.

1,399,729.

Specification of Letters Patent. Patented Dec. 13, 1921.

Application filed December 21, 1920. Serial No. 432,177.

To all whom it may concern:

Be it known that I, GEORGE R. ADAMS, a citizen of the United States, residing at Hillsboro, in the county of Hill and State 5 of Texas, have invented certain new and useful Improvements in Lifting-Jacks, of which the following is a specification.

This invention relates to new and useful improvements in lifting jacks.

10 The object of the invention is to provide a jack of the double acting type in which the rack member will be moved longitudinally during both the upward and downward swing of the actuating lever, thus 15 making for quick operation. A further object is to provide a jack in which the rack member may be raised by a half of the actuating lever, so that in places where the lever cannot be swung above a horizontal 20 position, the rack member may be operated. A further feature resides in a simple and efficient shifting means whereby the direction of movement of the rack member is reversed.

25 A construction designed to carry out the invention will be hereinafter described together with other features of the invention.

The invention will be more readily understood from a reading of the following specification and by reference to the accompanying drawings, in which an example of the invention is shown, and wherein:

Figure 1 is a vertical sectional view of a jack constructed in accordance with my 35 invention and showing the actuating lever at the center of its stroke,

Fig. 2 is a cross-sectional detail on the line 2—2 of Fig. 1,

Fig. 3 is a detail of the shifting device, 40 showing the reversing arms swung apart for elevating the rack member,

Fig. 4 is a view of the same part from the opposite side,

Fig. 5 is a sectional detail showing the 45 parts reversed for lowering the rack member,

Fig. 6 is a sectional detail of the upper portion of the jack showing the parts in position to elevate said rack member and showing the parts in dotted lines after they 50 have been elevated by one stroke of the actuating lever,

Fig. 7 is a similar view showing the parts in position for lowering the rack member, and

Fig. 8 is a perspective view of one of the 55 reversing arms.

In the drawings the numeral 10 designates a suitable base carrying an upright standard 11 which may be cast integral with the base and is provided with vertical guides 12. 60 A rack member 13 is mounted in the guides of the standard and carries a saddle 14' at its upper end in which the part to be elevated may be received. The rack bar is rectangular and has internal racks 14 on opposite sides extending vertically thereof. Between the center of the standard and its top a transverse pivot bolt 15 is arranged and extends through the central opening of the member 13. The standard is chambered 70 at 11' and is open on each side so as to receive the fork or yoke 16 of an actuating lever 17 extending laterally from the standard. The yoke embraces the member 13 on each side and extends through one side of 75 the standard but could be extended through both sides to provide means for two persons to simultaneously operate the jacks.

Within the yoke 16 a pair of dogs 18 and 19 respectively, are pivoted on each side of 80 the bolt 15, said dogs being oppositely directed and engaging the racks 14 on opposite sides of the member 13. A spreader spring 20 has its ends attached to the intermediate portions of the dog and is supported thereby 85 as is clearly shown in the drawings. It will be seen that when the lever 17 is swung one dog will be carried downward and the other will be carried upward. The teeth of the racks 14 are of such length that either dog 90 will travel over one tooth and engage the next during half the downward swing or stroke of the lever 17. By this arrangement if the lever 17 can be swung only from its lowermost position to its central position, 95 the member 13 will be elevated the distance of one tooth as will be obvious. This could not be accomplished with a single acting construction.

Each dog has a transverse pin 21 which 100 has a roller 22 rotatably confined on its outer end. The roller of the dog 18 co-operates with a swinging reversing arm 23, while the roller of the dog 19 co-operates with a swinging reversing arm 24. The arms are pivoted at their upper ends to the outer side of the standard 11 and have their lower ends connected by a coiled spring 25. A spreader

26 is pivoted to the standard 11 between the arms and is provided with a reversing bar 27 extending upwardly to a slot 28 in the housing 29 on the side of the standard and in 5 which the arms and spreader are inclosed. When the arms are engaged by the concentric edges of the spreader as is shown in Figs. 3 and 4, said arms are spread apart and the spring 25 is under tension. The spreader 10 has converging faces 26'. By swinging the bar 27 to the opposite end of the slot 28 the spreader 26 is rotated so as to bring the faces 26' between the arms so that the latter are swung into contact with said faces and 15 drawn together by means of the spring 25 as is shown in Fig. 5.

The arm 23 has an inclined guide flange 23', while the arm 24 has an inclined flange 24', said flanges being directed oppositely. 20 The lower flanged ends of the arms engage the roller 22 through slots 29' in one side through the side of the standard 11. It will be seen that when the arms are spread apart the dogs will be in engagement with the 25 teeth 14 and the flanges of the arms will be held out of the path of either of the rollers 22. Thus as the lever 17 is swung downwardly the dog 18 will be carried downwardly over the teeth of its rack, while the 30 dog 19 will remain in contact with the teeth of its rack and elevate the member 13. During this downward movement of the lever 17, the dog 18 will slip over two teeth, one during each half of the swing or stroke of said lever. 35 When the lever 17 is swung upwardly the dog 18 will remain in contact with its rack, while the dog 19 will slip over the teeth of its rack. In this manner the rack member 13 will be quickly elevated.

40 When it is desired to lower the member 13, the bar 27 is swung so as to shift the parts and reverse the operation. The arms will be brought toward each other by the spring 25 and occupy the position shown in Fig. 5. When the lever 17 is at either end of its stroke one of the rollers 22 will be engaged by the lower end of its respective arm and held out of engagement with its rack 14; while the roller 22 of the other dog will be 45 above and over the inclined flange of its respective arm. Referring to Fig. 5, it will be seen that the roller 22 of the dog 19 is in engagement with the lower end of the arm 24, while the roller of the dog 18 is above the flange 23'. The lever 17 is in its uppermost position as is shown in Fig. 7. With the parts in this position the dog 18 is supporting the member 13, and the dog 19 is out of engagement with its rack. When the lever 50 17 is swung downwardly the roller of the dog 18 comes into engagement with the flange 23' and rides down the same; while the roller of the dog 19 after traveling a short distance up the arm 24 rides onto the flange 24'. 55 From this it will be seen that the dog 18 will

be withdrawn from its rack and the dog 19 thrown into engagement with its rack. The spreader spring 20 has an additional function in this operation, because the dog 18 cannot be withdrawn from its rack until the 70 dog 19 has entered its rack and sustained the load. When the parts are in the position shown in full lines in Fig. 7, the tension of the spring 25 will overcome the spreading action of the spring 20; however when the 75 lever 17 reaches the end of its stroke the spreader spring 20 will assume the position shown in dotted lines, whereby the dog 18 will be withdrawn and the dog 19 drawn into its rack. Until the spring 25 overcomes the 80 action of the spring 20, the dog 18 will remain in engagement with its rack 14. When the lever 17 is thrown upwardly the action is reversed as will be clearly understood. Each dog is moved the distance of two teeth on its 85 rack bar at each stroke, so that a half stroke will move it one tooth and permit the operation of the jack as is apparent.

It is obvious that changes may be made in the arrangement and dimensions without departing from the spirit of the invention and all such changes and modifications which come within its scope are included. 90

What I claim is:

1. In a double acting jack, a standard, a 95 rack-member slidably engaging the standard and having a longitudinal opening and spaced longitudinal racks upon opposite sides of said opening, an actuating lever pivoted upon the standard at a point near the longitudinal opening of the rack-member, dogs mounted within the longitudinal opening of the rack-member and pivotally connected with the lever upon opposite sides of its pivot and arranged to engage the 100 racks, a spring connecting the dogs and serving to shift them outwardly into engagement with said racks, a pair of retracting arms pivotally connected with the standard upon opposite sides of the pivot of the 105 lever and provided with inclined flanges, lateral extensions carried by the dogs to engage the inclined flanges, a spring connecting the retracting arms to move them inwardly, and a movable member arranged 110 between the retracting arms and contacting therewith and adapted to shift them outwardly. 115

2. In a double acting jack, a standard, a 120 rack-member slidably engaging the standard and having a longitudinal opening and spaced longitudinal racks upon opposite sides of said opening, an actuating lever pivoted upon the standard at a point near the longitudinal opening of the rack-member, dogs mounted within the longitudinal opening of the rack-member and pivotally connected with the lever upon opposite sides of its pivot and arranged to engage the 125 racks, a spring con- 130

necting the dogs and serving to shift them outwardly into engagement with said racks, a pair of retracting arms pivotally connected with the standard upon opposite sides of the pivot of the lever and provided with inclined flanges, lateral extensions carried by the dogs to engage the inclined flanges, yielding means to move the retracting arms inwardly toward each other, a pivoted spreading element secured to the standard and arranged between the retracting arms and adapted to swing them outwardly, and a manually operated element to move the pivoted spreading element.

3. In a double acting jack, a standard, a rack member movable vertically of the standard, an actuating lever pivoted on the standard, dogs carried by the lever on opposite sides of its pivot point and engaging the rack member, a spreader spring disposed between the dogs and connected therewith, retracting arms pivoted on the standard, the dogs having portions adapted to engage the arms for retracting the dogs from the racks of the movable member, and means for moving the arms out of operative relation to the dogs.

4. In a double acting jack, a standard, a rack member movable vertically of the

standard, an actuating lever pivoted on the standard, dogs carried by the lever on opposite sides of its pivot point and engaging the rack member, a spreader spring disposed between the dogs and connected therewith, retracting arms pivoted on the standard, the dogs having portions adapted to engage the arms for retracting the dogs from the racks of the movable member, a spring connecting the retracting arms to move them inwardly toward each other, means for moving the arms out of operative relation to the dogs, and means for releasing the arms to actuate the dogs.

5. In a double acting jack, a standard, a rack member having internal racks and movable vertically of the standard, an actuating lever pivoted on the standard, dogs pivoted to the lever on opposite sides of its pivot point and engaging the racks of the member, a spreader spring having its ends connected with the swinging ends of the dogs, rollers carried by the dogs, a pair of arms pivoted on the standard, a coiled spring connecting the swinging ends of the arms, the rollers being disposed between the arms, a spreader arranged between the arms and engaged thereby, and means for springing the spreader to spread the arms apart.

In testimony whereof I affix my signature.

GEORGE R. ADAMS.
